UNITED STATES PATENT OFFICE.

JOHN ROWLAND TORRANCE, OF BITTON, ENGLAND.

GRINDING OR CRUSHING MILL.

Application filed February 25, 1922. Serial No. 539,260.

To all whom it may concern:

Be it known that I, JOHN ROWLAND TORRANCE, a subject of the King of Great Britain, residing at Bitton, England, have
 5 invented certain new and useful Improvements in and Relating to Grinding or Crushing Mills, of which the following is a specification.

The present invention relates to improvements in and relating to grinding or crushing mills and particularly in such mills to improved means for transmitting a drive from one rotating member to another, the members being eccentrically disposed.
 10 The present invention will be hereinafter described in relation to disc and the like grinding mills, particularly those, whether suited or adapted to dry grinding or to grinding fluids or mixtures which become fluid
 15 after grinding, of the kind consisting of an upper perforate grinding organ which forms a receptacle for the material to be ground and the lower face of which forms a grinding surface; the other grinding surface being a rotating disc which bears against the grinding surface of the receptacle, and in which the grinding members are two flat discs of stone, porcelain, metal or like, and the grinding members while held in the required proximity with each other grind one over the other with a compound relative rotary and lateral bodily movement.
 20

In the hereinafter described embodiments of mills of this kind the compound rotary
 25 and lateral bodily movement of the running stone is imparted in known manner either by means of a crank or eccentric pin on which rotates a driving sleeve connected to the grinding disc, on the one hand, or by
 30 means of a shaft eccentrically mounted free to rotate in a rotatable sleeve, on the other hand.

In either of the above mentioned types of mills the difficulty presented is to impart
 35 drive of rotation to the sleeve on the crank or eccentric pin, or to the shaft in the eccentric sleeve, from an eccentrically disposed member.

The usual drives by internal ring and pinion gear, and mechanisms of the horn or prong type, are open to the objection of keeping in step with the eccentric cycle changing as they do in phase with the eccentric cycle, and constantly maintaining the thrust at the same point, setting up severe heat, which causes seizures and breakages
 40

and militates against fine grinding, so much so, that it becomes impossible or very difficult to produce a mill of the dimensions suited for serious work, i. e., a profitable output 60 of a high quality product.

Now an object of the present invention is to overcome the above disadvantage by realising a balanced drive of rotation of the running stone from a member eccentrically disposed with respect thereto through the mediation of a third member which rotates concentrically with respect to the running stone and is so coupled that the point of drive is constantly maintained to move out of phase 65 with the eccentric cycle, the medial member being connected to exert or react to torque which is balanced or equal on opposite points of the axis.

The medial member being concentric with the running stone is eccentric to the member to which it is connected to receive drive, and for the point of drive to be constantly maintained and to move out of phase with the eccentric cycle, a single pin and slot connection, or a connection of this character serves. In the hereinafter described example in which the medial member is a sleeve which is driven from a gear eccentrically mounted with respect to the sleeve, a single lug on 70 the gear engages a radial slot in the sleeve, the slot being formed so as to accommodate the lug at any position in its eccentric path with respect to the slot.

The present invention may be conveniently 75 and advantageously carried into effect as hereinafter appears, reference being had to the accompanying drawings, in which:—

Fig. 1 shows a sectional elevation of the mill.

Fig. 2 a part sectional plan on the line 2—2 (Fig. 1) of worm wheel bracket, worm-shaft, worm and spur wheel.

Fig. 3 a part sectional plan on the line 3—3 (Fig. 1) of the trough showing front 100 scraper and bottom disc.

Fig. 4 a part sectional plan on the line 4—4 (Fig. 1) showing the sweeper and operating gear as described below.

Figs. 5 and 6 are enlarged sectional elevation and plan of the drive as applied to a crank or eccentric pin type of mill, Fig. 6 being taken substantially on the line 6—6 (Fig. 5).

Figs. 7 and 8 are enlarged sectional elevation and plan of the drive as applied to an eccentric shaft type of mill, Fig. 8

being taken substantially on the line 8—8 (Fig. 7).

Fig. 9 is a part sectional plan of the drive applied to operate a scraper to sweep out the 5 trough.

Fig. 10 is a part sectional elevation taken on the line 10—10 of Fig. 11.

Fig. 11 is a plan view of the driving head.

In application to the aforesaid crank or 10 eccentric pin type of mill, and referring to Figs. 1 to 6, the medial drive sleeve *a* is rotatably mounted on a crank or eccentric pin *b* on the upper end of the mill shaft *c*. the upper end of the sleeve is provided as a 15 spigot end with a ball head or top *d* to receive the lower grinding member *g* to which it transmits motion through a cross pin *h* fixed in the spigot, the pin *h* engaging with slots diametrically opposite in the boss *e* 20 of the retaining dish *f* of the lower grinding member *g*. The slots are given sufficient depth to allow the stone to swivel on the ball head *d*.

i is the upper stone which may be water 25 cooled.

The drive of the sleeve *a* is effected by pin or lug *j* and relieved slot connection *k* 30 between a boss *l* of a gear *m* rotatably mounted on the outside of the shaft bearing, and the sleeve, the slot *k* preferably being 35 radially disposed in a ring-like expansion *o* of the lower end of the sleeve *a* and being appropriately relieved to accommodate the eccentric relationship of the connected members, *a* and *m* respectively.

In a constructional form of paint or like mill as illustrated, the main vertical bearing is formed in the long boss *p* of a bracket *r* bolted between side members *s* of the mill 40 frame, and in this long boss *p* the vertical shaft *c* revolves at the speed of the orbital motion, transmitted through worm gearing *t*, *v*. The crown bevel wheel *m* positioned by a collar revolves about a liner *n* secured 45 by set pins *x*.

On the eccentric part *b*, of the shaft *c* the driving head or sleeve *a* fits, but free to 50 revolve at the same speed as the bevel wheel *m*, the slot *k* in the bottom of the driving head *a* engaging the tooth *j* on the bevel wheel *m*. Interposed between the shaft *c* and the driving head *a* is a bronze liner *y* which is free to revolve on the shaft *c*, or in 55 the bore of the driving head *a*.

The grinding thrust between the head or sleeve *a* and the shaft *c* is taken by a ball thrust bearing *l* fitted in the head or sleeve *a*.

Referring to Fig. 4 a pinion or star wheel 60 2, having four teeth for example, may be rotatably mounted upon the neck of the driving head *a*, to engage with an internal ring gear 3, having for example thirteen teeth, fixed in the centre of the trough 4.

65 The orbital motion of the head *a* will cause

the pinion 2 to rotate slowly on the head, in a reverse direction, and may be used to operate a scraper 5 fixed to the pinion 2 to sweep out the trough 4. 6 designates a hinged scraper yieldingly urged as by a 70 spring 6a against the edge of the running stone *g*. The foot-step thrust is taken on a radially seated ball bearing 7. Provision is made to compensate for wear on the grinding members by means of the screwed strut 75 8 on the cup in which the thrust member is fitted.

A bevel pinion 9 fast on a main driving shaft 10 drives the bevel wheel *m*. Mounted on the neck of the driver gear 9 to rotate 80 therewith is a spur wheel 11 which drives a spur wheel 12 on the shaft 15 for driving the worm gearing *t* and *v*.

The shaft *c* is free to slide through the bore of the worm wheel *v*, the drive to the 85 shaft being obtained by means of a feather.

In operation, the shaft *c* is revolved slowly in its bearing by the worm gearing *t*, *v*, and the top part *b* of the shaft being turned eccentric to the portion in the bearing moves 90 in an orbit round the common centre line of the shaft, and mill. Mounted upon the eccentric top portion *b* of the shaft *c* is the head or sleeve *a* free to rotate thereon, this head is driven by the bevel wheel *m* through the tooth *j* and slot *k*, which allows the necessary sliding movement due to the wheel *m* and head or sleeve *a* being eccentrically disposed, the bevel wheel *m* and head *a* running at a speed which is high in relation to that 95 of the shaft.

With the discs having an ever varying cross or lateral—in addition to the circular—motion, the grinding surfaces do not deteriorate, but retain their true form indefinitely, and re-dressing or truing up 100 periodically is but little if at all required.

16 and 17 indicate an oil feed delivery for the shaft *c*.

In application to the aforesaid eccentric sleeve type of mill and referring to Figs. 7 and 8, the lower portion 18 of the eccentric sleeve 19 is formed exteriorly concentric with the bore which receives the shaft 20 that it is desired to drive with a balanced 115 torque or turning effort. Otherwise the eccentric sleeve is formed exteriorly eccentric to the bore.

On the eccentric sleeve 19 immediately 120 above the exterior concentric portion thereof is rotatably mounted a gear, for example, a bevel gear 21 which is suitably driven, and under this gear and on the exterior concentric portion 18 of the eccentric sleeve 19 is rotatably mounted a drive sleeve 22 which is driven from the gear by a lug or pin and slot 23, 24, the slot 24 preferably being formed in a ring-like expansion at the upper end of the sleeve, and being relieved 125 for accommodating the varying positions as- 130

sumed by the lug or pin 23 on the boss of the gear 21 by virtue of the eccentric relationship of the connected members, the relative sliding motion of the lug and slot 5 realizing the transmission of a free and smooth motion from the gear 21 to the sleeve 22.

The drive sleeve 22 and the shaft 20 which is eccentrically mounted in the rotatable sleeve 19 and projects beyond it at the lower end can now be so coupled together as to ensure that the torque or turning effort shall be equal at opposite points of the shaft and the thrust on the shaft bearings reduced to a minimum.

A simple connexion for this purpose comprises a pair of slots 25 diametrically opposite in a ring-like expansion 26 of the lower end of the medial drive sleeve 22, and corresponding pins 27 on the shaft 20 to engage the slots 25. Other balanced connections are obviously available.

The eccentric sleeve 19 is rotatably mounted in a main neck bearing 28 forming a fixed 25 part of the casing of the grinding members and is driven by a worm wheel 29 fast on the sleeve 19.

Drive is imparted to the worm wheel 29 and the bevel gear 21 in a similar manner 30 as that hereinbefore described with reference to the eccentric pin type of mill.

By changing the gearing such as 11, 12, the velocity ratio up and down between the rotatory drive and the lateral bodily drive 35 may be varied as desired.

In both examples of mill hereinabove given the drive is freely and smoothly transmitted through the medial member α or 22 to the running stone g , and thrust and wear 40 is distributed evenly over the bearing surfaces as the point of drive is constantly moving forward and out of step with the eccentric cycle and the drive to the running stone is balanced for all practical purposes, 45 the torque being equally divided on opposite sides and consequently the thrusts are opposite and opposing. Consequently the mill runs remarkably cool under all working conditions, and the grinding is notably fine, 50 consistent, and profitable.

What I claim is:

1. The combination in a grinding mill of the kind described, of co-operating flat grinding members, means for imparting to 55 one of said grinding members an orbital movement, abaxial members for imparting a drive of rotation to said orbital moving grinding member at the same time as the orbital movement, and a single pin and slot 60 driving coupling connecting the abaxial members such that the angular point of drive between the said abaxial members remains unchanged and moves out of phase with the orbital movement of the said grinding member.

2. A grinding mill of the kind described comprising co-operating flat grinding members, a shaft bearing, a shaft rotatably mounted therein, an eccentrically disposed upper portion on said shaft, a sleeve rotatably mounted on the eccentrically disposed upper portion, a connection between said sleeve and one of the grinding members for imparting a rotatory drive thereto, means for rotating the shaft, means for rotating the sleeve comprising a driving member concentrically disposed with respect to the shaft and a driving coupling connecting said driving member and said sleeve whereby the angular point of drive between the driving member and the sleeve remains unchanged and moves out of phase with the orbital movement of the sleeve, substantially as described.

3. The combination with a grinding mill as claimed in claim 2 hereof of a trough scraper and means for driving the scraper in a reverse direction to the orbital movement of the running grinding member substantially as described.

4. The combination with a grinding mill as claimed in claim 2 hereof of an edge-scraper and means for yieldingly urging said scraper against the running grinding member, substantially as described.

5. A grinding mill of the kind described comprising co-operating flat grinding members, a shaft bearing, a shaft rotatably mounted therein, an eccentrically disposed upper portion on said shaft, a sleeve rotatably mounted on the eccentrically disposed upper portion, a connection between said sleeve and one of the grinding members for imparting a rotatory drive thereto, a common main driving shaft, means for rotating the sleeve, and means comprising intermediate worm gearing for rotating the shaft substantially as described.

6. The combination with a grinding mill as claimed in claim 5 hereof of a trough scraper and means for driving the scraper in a reverse direction to the orbital movement, substantially as described.

7. The combination with a grinding mill as claimed in claim 5 hereof of an edge-scraper and means for yieldingly urging said scraper against the running grinding member, substantially as described.

8. A grinding mill of the kind described comprising co-operating flat grinding members, a shaft bearing, a mill shaft rotatably mounted therein, an eccentrically disposed upper portion on said shaft, a sleeve rotatably mounted on the eccentrically disposed upper portion, a connection between said sleeve and one of the grinding members for imparting a rotatory drive thereto, a common main driving shaft, means for rotating the sleeve, a counter shaft, means comprising worm gearing carried by said counter shaft for rotating the mill shaft, and gearing in-

- introduced between the main shaft and the counter shaft for the purpose set forth.
9. A grinding mill of the kind described comprising co-operating flat grinding members, a shaft bearing, a shaft rotatably mounted therein, an eccentrically disposed upper portion on said shaft, a sleeve rotatably mounted on the eccentrically disposed upper portion, a connection between said sleeve and one of the grinding members for imparting a rotatory drive thereto, a common main driving shaft, means for rotating the sleeve comprising a bevel gear the driven bevel being rotatably mounted on the shaft bearing, a radially moving coupling connecting the said driven bevel and the said sleeve, and means for rotating the shaft comprising worm gearing, substantially as described.
10. A grinding mill of the kind described comprising co-operating flat grinding members, a shaft bearing, a mill shaft rotatably mounted therein, an eccentrically disposed upper portion on said shaft, a sleeve rotatably mounted on the eccentrically disposed upper portion, a connection between said sleeve and one of the grinding members for imparting a rotatory drive thereto, a common main driving shaft, means for rotating the sleeve comprising a bevel gear, the driven bevel being rotatably mounted on the shaft

bearing, a radially moving coupling connecting the said driven bevel, and the said sleeve, a counter shaft, means comprising worm gearing carried by said counter shaft for rotating the mill shaft, and gearing introduced between the main shaft and the counter shaft for the purpose set forth.

11. A grinding mill of the kind described comprising in combination co-operating flat grinding members, abaxial members for imparting, a drive of rotation through abaxial members, means for imparting the orbital movement, means for imparting the rotatory movement, and a radial movable single pin and slot coupling connecting the said abaxial members for the purpose described.

12. In a grinding mill as claimed in claim 11 hereof the combination of a trough scraper and means for driving said scraper in a reverse direction to the orbital movement of the running grinding member, substantially as described.

13. In a grinding mill as claimed in claim 11 hereof the combination of an edge-scraper and means for yieldingly urging said scraper against the running grinding member, substantially as described.

In testimony whereof, I affix my signature.

JOHN ROWLAND TORRANCE.
